and is a part of the door or window. It will be seen that the edge of the door or window is not in contact with the frame, but is offset from it. The door or window is held in position by a hinge arrangement which is to be described.

UNITED STATES PATENT OFFICE

2,604,674

CLOSURE HINGE ARRANGEMENT

Peter Johnson, Penticton, British Columbia,
Canada

Application September 6, 1949, Serial No. 114,263

2 Claims.

(Cl. 20—53)

1

This invention relates to hinge arrangements for closures, such as windows, doors, panels, and the like.

An object of the present invention is the provision of a hinge arrangement which makes it possible to open a closure from either side thereof.

Another object is the provision of a hinge arrangement for closures, particularly windows, which enables the closure to be opened and reversed.

This invention is particularly applicable to casement windows and doors and it is described in connection with the former, but it is to be understood that it may be used with any type of closure.

At the present time, all doors and casement windows may be opened from one side only thereof. Thus, once these windows and doors are installed, they must always open them the same way, unless their hinges are changed over to the opposite side, in which case they must always be opened the new way. For example, when a person now buys a refrigerator, he selects one with the door opening in the most convenient way for the room in which it is to be placed. If the refrigerator is shifted to another part of the room or to another room, the door may not be opening the right way, but nothing can be done about it.

The present invention overcomes these difficulties by providing a hinge arrangement by means of which the door or window may at any time be opened from either side. This hinge arrangement preferably has two hinge elements for both top and bottom of a closure. Each of these elements consists of an arm, the length of which is approximately equal to the width of the closure. A hinge plate is pivotally connected to one end of the arm and is adapted to be fastened to the opening with which the closure is associated. Another hinge plate is pivotally connected to the opposite end of the arm and is adapted to be fastened to the closure at the side thereof remote from the first hinge plate.

An example of this invention is illustrated in the accompanying drawings, in which:

Figure 1 is a plan view of one hinge element as it would appear in closed position,

Figure 2 is an elevation of one end of this element,

Figure 3 is an elevation of the opposite end of the hinge element,

Figure 4 is a plan view of another hinge element which co-operates with the one shown in Figure 1, also in closed position,

Figure 5 is an elevation of one end of the element of Figure 4,

2

Figure 6 is an elevation of the opposite end of the element of Figure 4.

Figure 7 is a perspective view of the window open in one direction.

Figure 8 is a perspective view of the window reversed in relation to its opening.

Figure 9 is a view similar to Figure 8 with the window open in the opposite direction, and

Figure 10 is an elevation of the upper part of

10 a window, showing the hinge elements in section.

Referring more particularly to Figures 1 to 3 of the drawings, 10 is a comparatively long arm, and 11 is a hinge plate pivotally connected to one surface of the arm at one end thereof by means of a pintle 12. Another hinge plate 14 is pivotally connected to the opposite surface of the arm at the opposite end thereof by means of a pintle 15.

Figures 4 to 6 illustrate a second arm 20 which is adapted to co-operate with the arm 10. The arm 20 has projections 21 and 22 projecting outwardly from its opposite ends from the same side thereof. A hinge plate 24 normally lies in a plane at right angles to the plane of the arm 20, and has a lug 25 at one corner thereof lying substantially at right angles to the plane of said plate. The lug of this hinge plate is pivotally connected to the projection 21 at the end of the arm by a pintle 26. Another hinge plate 29 is pivotally connected to the extension 22 at the opposite end of the arm by a pintle 30.

Referring to Figures 7 to 10, 35 represents a frame around the opening 36 with which the closure or window 37 is associated. It is to be understood that a special frame, as shown, may be provided or the wall in which the opening is located may actually form this frame. In the preferred form of the invention, a pair of co-operating arms 10 and 20 are located at both the top and bottom of the window.

In the illustrated example, the hinge plate 14 is fastened to the top of the frame 35 at one side thereof by screws or other suitable means. It is preferable that this plate be let into the frame, as clearly shown in Figure 7. The other hinge plate 11 of the arm 10 is fastened to the upper edge 40 of the window at the side thereof which is normally remote from the plate 14. This plate is preferably let into the top of the window, as shown.

50 The hinge plate 24 of the second arm 20 is fastened to the side of the frame 35 adjacent the hinge plate 11 and placed in such a position that said arm 20 is slightly below the arm 10 when the window is closed. The hinge plate 29 of the arm 20 is fastened to the upper edge of the window 37

3

at the side thereof normally remote from the plate 24. The plate 29 is positioned at a level lower than the plate 11 which is fastened to the opposite side of the window in order to allow the arm 10 to move over the projections 21 and 22 of the arm 20 when the window is closed.

Suitable stop means is provided for preventing the window from pivoting from beneath the arm 20 when it is opened in the direction illustrated in Figure 9. This may be in the form of a shoulder 41 extending along the top of the window. With this arrangement, the arm 20 lies alongside this shoulder when the window is closed or is in the open position shown in Figure 9. The arm 10 lies over the shoulder when the window is closed or is in the open position shown in Figure 7.

By referring to Figure 10, it will be seen that the pintle 15 is directly in line with the pintle 30. This is the case when the window is closed or opened to the right as shown in Figure 7. Similarly, Figure 10 shows that the pintle 12 is directly in line with the pintle 26. This also is the case when the window is closed.

Any suitable means may be provided for holding the window in its closed position. In this example, a latch 44 having an operating handle 45 is provided at each side of the window. Each latch co-operates with a keeper 46 secured to its side of the frame 35. Stops 48 are provided along the top and bottom of the frame at one side thereof in order to prevent the window from opening outwardly to the wrong side of the opening.

When the window is to be opened to the right, as illustrated in Figure 7, the appropriate latch is operated and the window is swung open on pintles 15 and 30. At this time, the arm 10 swings open with the window while the arm 20 remains in its normal position within the frame. As the arm 10 is connected to the hinge plate 14, the arm 20 cannot move out of its normal position until the window is completely open, that is, until it is substantially parallel with the window opening 36. When this position is reached, it is possible to move the edge of the window outwardly from the pintle 15, as the arm 20 may now pivot outwardly on its pintle 26. If the window is moved far enough, it will assume the position shown in Figure 8. At this time, the surface of the window which normally faces outwardly is facing the window opening, thus enabling the outer surface of the window to be cleaned. When the window is swung back into the position shown in Figure 7, it may be swung into its normal closed position.

When the opposite latch is operated, the window may be swung into the position shown in Figure 9. When this is done, the window swings on the pintles 12 and 26 and the arm 10 remains in its normal position within the frame. This is possible because the pintles 12 and 26 are directly in line. The window cannot be reversed from this position since the shoulder 41 prevents its inner edge from being swung away from the frame.

4

The hinge arrangement at the bottom of the window is a duplicate of the one at the top and, therefore, it functions in the same manner. As the arms 10 and 20 reach from one side of the window frame to the opposite side of the window when the latter is closed, the length of each of said arms is substantially equal to the width of the window.

What I claim as my invention is:

1. In combination with a closure, such as a door, window and the like, having a shoulder extending along a horizontal end thereof and spaced from one of its faces, and a frame therefor having substantially vertical sides and horizontal ends, said closure being adapted to be moved into and out of the frame, a hinge arrangement comprising an arm substantially as long as the width of the closure and lying over the closure shoulder when the closure is positioned within the frame, hinge plates pivotally connected to opposite surfaces at opposite ends of said arm, a second arm of substantially the same length lying on the closure end beside the shoulder when the former is positioned in the frame, hinge plates pivotally connected to the same surface of the second arm at opposite ends thereof, one of said plates of the second arm lying in a plane at right angles to the plane of the arm, the two hinge plates of the first arm being connected to one horizontal end of the frame near one side thereof and to the shoulder near the side of the closure remote from the plate respectively when the closure is in position in the frame, the angular hinge plate of the second arm being connected to the vertical side of the frame remote from the plate connected to the frame end, and the other hinge plate of said second arm being connected to the closure end remote from the other arm plate connected to the shoulder, the frame end being recessed to receive the hinge plate connected thereto, and the frame side being recessed to receive the angular plate connected thereto.

2. A hinge arrangement as claimed in claim 1 in which the shoulder is recessed to receive the hinge plate of the first arm connected thereto, and the closure end is recessed to receive the hinge plate of the second arm connected thereto.

PETER JOHNSON.
